UNITED STATES PATENT OFFICE.

RALPH P. FOX, OF HARRISBURG, PENNSYLVANIA.

WHEELED TOY.

Application filed March 13, 1922. Serial No. 543,250.

To all whom it may concern:

Be it known that I, RALPH P. FOX, a citizen of the United States, residing at Harrisburg, in the county of Dauphin and State of Pennsylvania, have invented new and useful Improvements in Wheeled Toys, of which the following is a specification.

This invention comprehends the provision of a wheeled toy, which is very simple in construction, and designed to afford considerable pleasure and amusement to young children, the toy embodying amongst other features, a platform which is rotated incident to the movement of the toy in its entirety over the ground or surface, the platform supporting a figured toy of any design.

The nature and advantages of the invention will be better understood when the following detailed description is read in connection with the accompanying drawing, the invention residing in the construction, combination, and arrangement of parts as claimed.

In the drawing forming part of this application, like numerals of reference indicate similar parts in the several views, and wherein:

Figure 1 is a side elevation of the toy, partly in section.

Figure 2 is a bottom plan view.

Figure 3 is a rear elevation.

Figure 4 is a perspective view of the handle support.

Referring to the drawing in detail, 10 indicates spaced ground wheels which are connected by an axle 11, and while these elements may be constructed from any suitable material, but they are preferably constructed of wood. Surrounding the axle 11 is a sleeve 12 preferably constructed of metal, the sleeve terminating in a flange 13 arranged adjacent one of the wheels 11, while the other end of the sleeve is spaced from the adjacent ground wheel 10 as illustrated in Figures 2 and 3. Supported by the axle 11 between one ground wheel 10 and the adjacent end of the sleeve 12 is a gear 14, which meshes with a ring gear 15 secured in any suitable manner to the underside of a platform 16.

This platform is mounted for rotation in a manner to be presently described, and manifestly, rotated when the toy is moved over the ground or surface, or in other words, incident to the rotation of the ground wheels 10. The toy is manipulated through the instrumentality of a handle 18, which is pro-

vided with a support or rest 19 at an appropriate point in its length.

The handle is supported by means of a support of the character illustrated in Figure 4, and which support is preferably formed from a single piece of metal, and possesses a substantially U-shaped configuration. The spaced parallel portions 19 and 20 of this support straddles the sleeve 12 which surrounds the axle 11, and the portion 20 of said support is slightly curved as at 21 to conform to the curvature of the sleeve in the manner illustrated in Figure 1. The support in its entirety is soldered or otherwise rigidly secured to the sleeve 12. The portion 19 of the support is provided with extensions 22 which are adapted to be bent downwardly, and thence inwardly, and arranged in overlapped relation as at 23, reposing upon the portion 20 of the support. As illustrated in Figure 4, these extensions are wholly disposed to one side of the curved portion 21, and assists in preventing casual separation of the support from the sleeve 12. The overlapped portions 23 of the extensions, as well as the parallel portions 19 and 20 of the support are provided with aligned openings indicated at 24, and which openings register with an opening formed in the adjacent end of the handle to receive the pivot 25. As shown in Figure 1, the handle is received by the open end of the support, and after the pivot 25 is passed through the support and handle, a nut 26 is threaded on the lower end of the pivot to hold the parts fixed relatively. A bushing 27 surrounds the pivot 25 and is interposed between the platform and the handle support. The toy is very simple in construction, and can be manufactured and sold at a very nominal cost. The toy figure indicated at 28 is secured to the platform, and rotates with the latter, to afford young children considerable pleasure and amusement.

It is to be understood that the toy figure 28 can vary in shape and configuration without departing from the spirit of the invention.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:—

1. A toy of the character described comprising spaced wheels, an axle connecting said wheels, a stationary sleeve surrounding the axle, a handle, a handle support formed from a single piece of material and including spaced parallel portions straddling said sleeve and secured thereto, extensions projecting from all of said portions and arranged in overlapped relation upon the other of said portions, said support receiving said handle, a platform, a toy figure on said platform, a pivot for the platform, said pivot being passed through said handle and its support, and means for rotating said platform incident to the rotation of said wheels.
2. A top of the character described comprising spaced wheels, an axle connecting said wheels, a stationary sleeve surrounding the axle, a handle, a handle support formed from a single piece of material and including spaced parallel portions straddling said sleeve and secured thereto, extensions projecting from all of said portions and arranged in overlapped relation upon the other of said portions, said support receiving said handle, a platform, a toy figure on said platform, a pivot for the platform, said pivot being passed through said handle and its support, and means for rotating said platform incident to the rotation of said wheels.

In testimony whereof I affix my signature.

RALPH P. FOX.
